UNITED STATES PATENT OFFICE.

JOSEPH BECKER, OF WASHINGTON, DISTRICT OF COLUMBIA, ASSIGNOR TO EASTMAN KODAK COMPANY, OF ROCHESTER, NEW YORK, A CORPORATION OF NEW YORK.

FOCUSING-CAMERA.

1,240,788.

Specification of Letters Patent. Patented Sept. 18, 1917.

Continuation in part of applications Serial No. 26,647, filed August 11, 1900, and Serial No. 88,805, filed April 4, 1916. This application filed July 6, 1917. Serial No. 178,990.

To all whom it may concern:

Be it known that I, JOSEPH BECKER, a citizen of the United States, residing at Washington, in the District of Columbia, 5 have invented certain new and useful Improvements in Focusing-Cameras, of which the following is a specification.

The present application, identified for convenience of reference as Case Ax, constitutes the third and concluding part of a 10 single "continuous application" whose fundamental subject-matter, seen in Figure 57 of my Case A, now Patent 1,178,474, bears the three successive filing dates, to wit: 15 August 11, 1900, of my said case A; April 4, 1916 of my herein merged Case Ak, Serial No. 88,805; and July 6, 1917 of my present Case Ax.

A complete list of all my applications or 20 patents referred to more or less specifically in the present specification, comprises: my Case A, Serial No. 26,647, filed August 11, 1900, now Patent 1,178,474, issued April 4, 1916; my Case C, Serial No. 63,106, filed 25 June 4, 1901, now Patent 1,178,476; my Case Ag or division one of A, Serial No. 86,366, filed March 24, 1916; my Case Ah or sole division of C, Serial No. 87,977, filed March 31, 1916; my Case Ak or division 30 three of A, Serial No. 88,805, filed April 4, 1916; my present Case Ax, Serial No. 178,990, filed July 6, 1917.

Fig. 57 of my said Case A is diagrammatic, as noted in line 91, page 18, of my 35 said Case A, and it therefore is not well suited to present purposes, for several reasons, to wit: First, it is entirely dependent on other widely separated parts of the Case A specification, for a disclosure of the theoretical principles involved; secondly, it incorrectly shows the contacting faces of the 40 terminal teeth on its lever arms 131', 132' as flat, instead of rounded to agree with the showing in Fig. 55, where they might even 45 be made more curved, for clearness; thirdly, its cam edge 134' is not sufficiently inclined or non-radial, for any ordinarily assumable lens and camera dimensions.

The main object of the present application, Case Ax, is to cure all of the just 50 enumerated deficiencies; and a secondary object is to add an angular adjustment for the mirror 138 of the said Fig. 57, to permit of inclining the line of sight as in my said 55 Cases C and Ah.

The present invention consists in focusers of the special "two image type" referred to in Note 8, page 21, of my said Case A, as comprising two base line mirrors mounted obliquely at the end of the focuser base 60 line so that each faces the object and acts independently of the other to form its own separate image of the object, as in Figs. 39, 40, 41, 44, 45, 46, 52, 54, 57, 59, 60 of my said Case A, where Figs. 42, 47 and 48 are 65 likewise relevant.

Fig. 57, of this series, with slight improvements, is selected as main figure, or Fig. 1, of the present application, Case Ax, because it comprises, united and combined 70 in one structure, the greatest number of important features, to wit: (1) each of the two base-line mirrors M, M' mounted so as to face the object, as just stated; (2) the optically closer of the two base line mirrors 75 M made sufficiently large in extent to show the peripheral parts of the camera field and virtually provided with a relatively small central passage to admit rays coming from the more distant base line mirror M'; (3) a 80 special combination of totally reflecting prisms acting as such virtually perforated and optically closer base-line mirror; (4) a divergent lens to form a reduced and relatively close image of the, full size and distant, compound image formed by the said base-line mirrors; (5) means, such as a third 85 angularly adjustable plane mirror R, for erecting such finder image, and for adjusting the inclination of the line of sight Ejj' 90 to produce a "drop finder" effect such as noted in my said Case Ah; (6) pivoting, and symmetrical arrangement of, the two base-line mirrors M, M' to avoid parallactic 95 error; (7) the extremely simple non-radial cam k, k', as connecting gear between the focuser parts on the one hand, and the camera parts on the other hand.

Feature 6 is fully claimed in my said parent Case A; and feature 7 is fully claimed 100 in my said Case Ag or division one of A; hence, no claim will be made to either of these features 6 or 7 in the present application, Case Ax.

In the accompanying drawings: 105

Fig. 1 (reproduced from Fig. 57 of my said Case A, excepting as to four main features, to wit: (1) the angular adjustment of mirror R; (2) the exact plotting of the conjugate distances OF and F'O'; (3) the 110

necessarily greater inclination of the cam face kk' called for by such exactly plotted distances; (4) the complete diagram of all images formed by the focuser mirrors and 5 lens, is a side view of a focusing camera provided with my present improved form of focus and field finder showing the camera sharply focused on O , at O' , while the mirrors M and M' are held, by the correctly inclined cam edge kk' at the proper inclination to secure apparent coincidence of the 10 two reduced, but erect and positive, finder images j and j' of the said object point O .

Fig. 2 is a front view of the same camera 15 showing how the fundamental base line AA' of the focuser is met and bisected at B , by the principal axis of the camera, and is wholly contained in the vertical meridional plane of the camera objective.

20 Fig. 3 shows the finder image as it appears to the eye at E , Fig. 1, assuming that the object to be focused on is the letter "L" which it will be noted is seen both erect and positive, exactly as if viewed without a 25 finder, excepting that it is smaller and that it has at j' , a break which indicates that the camera is out of focus.

Fig. 4 is a scale of parts used in measuring the fundamental dimensions of Fig. 1, 30 each part being about 3 millimeters long in the camera if the latter be of the size that takes the standard 5 by 7 inch plate.

Figs. 5 and 6 are tables of the fundamental dimensions, both linear and angular, 35 that occur in Fig. 1.

Fig. 7 (corresponding to the two Figs. 41 and 13 of my said Case A) shows the simplest form of the two base-line mirrors M^2 and M^3 ; it also answers as a diagram of 40 what occurs when the mirrors M , M' of Fig. 1 are set in parallel relation, or for infinity, showing how the alined object points O , P , Q , are, in such case, reflected as two parallel series of images I , J , K and I' , J' , K' .

45 Fig. 8, comprising four separately numbered compartments 1, 2, 3, 4, illustrates what I mean by the terms "positive or negative" and "erect or inverted" as applied to four different finder images of the same letter F used as field object, F being, for present purposes, even more convenient than L used in Fig. 3.

Fig. 9 shows a perforated prism equivalent of Fig. 7.

55 Fig. 10 shows the unperforated built-up prism equivalent, of either Fig. 7 or Fig. 9, that is used in Fig. 1.

Fig. 11 is a perspective of the upper built-up prism of Fig. 10.

60 Fig. 12, shown as if made of a single piece of glass, illustrates how the central cemented surface element of the larger prism, in Fig. 11, has totally lost its reflecting power.

The camera proper, Fig. 1, comprises an 65 L-shaped frame 10, 11, whose upright part

10 supports the lens 12, and whose horizontal part 11 is provided with suitable guideways for the movable frame 13 which carries the ground glass, plate or film 14, and is connected with the upright 10 by the usual 70 bellows 15.

The upright part 10 has rigidly fastened thereto a vertical shelf-like bracket 20 which serves as base plate and support for all parts of the combined focus and field finder, whose 75 optical elements comprise three principal parts, to wit: first, two pivoted or base-line mirrors M , M' , whose stationary central points are indicated by dots A , A' , and which form two full size but "inverted" 80 and "negative" images I and I' of the object point O to be focused on, as in compartment No. 4 of Fig. 8; secondly, a stationary divergent lens D which forms the relatively close but reduced copies i , i' of 85 images I , I' , such reduced images i , i' being likewise "inverted" and "negative," as in compartment No. 4 of Fig. 8; thirdly, a stationary plane reflector R which reflects images i , i' , to form the images j , j' , constituting the true finder image, Fig. 3, where the object to be focused on is the letter L , seen both "erect" and "positive" as in compartment No. 1 of Fig. 8; that is to say the upper part of the letter is up, and its right-hand side is at the right, so that there is no 90 inversion of any kind present, in the final finder image jj' .

The exact relation of the two full size and alined images I , I' in Fig. 1, is made 100 plain by adding the two nonregistering or offset images J , J' of the closer axial point P . The intersections of the lens axis FF' by the two mirrors M and M' being at n and n' , respectively, it is furthermore evident that the image of OPn in mirror M is IJn , while the image of line OPn' in mirror M' is line $I'J'n'$. 105

The upper base line mirror M is rigidly mounted on a bell-crank 21, 22, which is pivoted to the base or shelf 20 by a pivot 23, whose axis produced passes through the central point A of mirror M and determines the axis of rotation of such first base-line mirror M . The lower base-line mirror M' is similarly mounted on a bell-crank 21', 22', which is pivoted to the base or shelf 20 by pivot 23' whose axis, produced, passes through the central point A' of the mirror M' and determines the axis of rotation of such second base-line mirror M' . 115

Arm 21 has a gear-tooth extension 24 which is held pressed against a similar gear-tooth extension 24' of arm 21', by means of a tension spring 25 connecting the horizontal members 22, 22' of the two bell cranks. 120

The lower arm 22' has a rearwardly projecting extension 26, 27, which plays freely in a channel 28 formed in bed 11 of the camera and whose upper rear edge kk' con- 130

stitutes a non-radial cam edge adapted to bear against the lower right-hand edge or corner k' of the movable frame 13, contact being insured at k' by the same before-mentioned tension spring 25, which, therefore, suffices to take up all lost motion and keep all parts of the combination in close working contact. When the camera is to be focused on left-hand infinity for instance, O' comes 10 up into coincidence with F', corner k' moves up to k'' , and the point k of the cam rises up into coincidence with k'' , where it makes contact with corner k' of the advanced frame 13 and holds the mirrors M and M' in 15 parallel relation. The angle tau (τ) or $kA'k''$ is evidently equal to one-half of angle omega (ω) or FOA', and the principal focus F is, in this case, identical with point G of Fig. 23 in my said case A, in which 20 figure the pivot A corresponds to pivot A', Fig. 1, of the present case. It also evidently corresponds to pivot A of the present case.

The pivoted mirrors M and M' therefore act as if each independently coöperated with 25 an imaginary stationary mirror set obliquely at B on the camera axis and corresponding to mirror N in Fig. 4 of my said Case A. That is to say the basic triangle of the focuser is not OAA' but triangle OGA', or 30 the equal triangle OGA and the basic angle of the corresponding theoretically exact or "radial cam" focuser is the obtuse angle r at G, which is identical with the angle " r at G" in the basic diagram, Fig. 23, of my said 35 Case A.

When the two base-line mirrors are turned from their parallel relation, such as the relation shown for mirrors M², M³ in Fig. 7, into an inclined relation, such as the relation shown for mirrors M, M' in Fig. 1, it should be noted: first, that the two images I and I' of Fig. 7 are moved inwardly, at equal rates, until they both fall 40 into alinement with A and A' as shown in Fig. 1; secondly, that if the planes of the inclined mirrors M, M', Fig. 1, be produced they will intersect in a point W which is the lowest point of the arc A'W described about O as center; thirdly, that the triangle WII' 45 thus determined is always exactly equal to the isosceles triangle OAA'.

These results are all dependent upon the fact that the chord WA of Fig. 1, bisects the angle OAI, thus fixing the angular position of mirror M; while the chord WA', 50 similarly bisecting angle OA'I', fixes the angular position of mirror M'.

Bisection at A' is rendered evident by noting that the angles a and b are separately equal to c , hence equal to each other; and bisection at A could be proved in the same manner.

The mirror R is shown as fixed at 45 degrees to determine a sight line Ejj' that is 65 horizontal. Its base 30, however, is pivoted

at 31 and has a clamp screw 32 passing through the arcuate slot 33, to permit of fixing the mirror at any other desired inclination with the object of lowering the finder image jj', and producing a "drop effect" 70 similar to that noted in my said Case C, and in my said case Ah division of C.

With reference to the nature of the finder image obtained, it should be noted: first, that any arrangement such as shown in Figs. 52, 54 and 59 of my said Case A has the disadvantage of forming a finder image that is both "inverted" and "negative" as in compartment No. 4 of my present Fig. 8; secondly that the arrangement shown in Fig. 60 75 of my said Case A forms a finder image that is "erect" but "negative" as in compartment No. 2 of my present Fig. 8; thirdly that the arrangement of present Fig. 1 forms a finder image that is both "erect" and "positive" as 80 in compartment No. 1 of my present Fig. 8. The present Fig. 1, therefore, has special practical advantages over all others and constitutes, in this particular respect, a novel form of field finder that is generally useful 85 in all cameras, even in those of the fixed focus type.

The two base-line mirrors in their simplest form comprise a simple reflecting plane M², Fig. 7, perforated at m' , and a simple 95 unperforated reflecting plane M³; and the evolution from such simplest form, to the built-up form of Fig. 1 is most easily traced through Figs. 9 to 12.

Substituting totally reflecting prisms for 100 the reflecting plates M², M³ of Fig. 7, produces the form seen in Fig. 9, where the upper prism must be provided with a perforation or well, but the result is not satisfactory because of the difficulty of making a sharp 105 flat wall perforation and because the walls, unless they taper exactly to the observer's eye, must conceal the meeting edges of the two images to be brought into registration. Another and more serious objection is that 110 the perforation acts as an opaque body in the prism and therefore cuts off a good part of the image. To avoid all these difficulties, I have devised the highly improved form, Fig. 10, in which a small prism 114 is cemented with Canada balsam to the under 115 side of an unperforated main prism 115. The compound prism thus formed, with prism 103^a, forms a combination exactly equivalent to what the form shown in Fig. 7 would be, if the upper reflecting plate M², 120 in such Fig. 7, could be made infinitely thin.

The compound or built-up prism of Fig. 10 is shown separately, and in perspective, by Fig. 11.

The addition of the small prism is equivalent in effect to the perforation of the large prism. It virtually provides the large prism with a wall-less perforation. That a hole should be virtually produced by the addi- 130

tion of matter is so paradoxical that I must explain the effect in full.

Where the prisms are in contact the cement, being of the same refractive index 5 as glass, unites the two prisms so intimately that the cemented surfaces virtually cease to exist and the glass of the small prism 114 becomes, in effect, continuous with that of the large prism 115. The two prisms are, 10 as it were, one solid mass of glass of the outline shown in Fig. 12, where the combination 114^a, 115^a is obviously as transparent to a vertical ray of light 117 as any plane-parallel plate of glass might be. The horizontal ray 118 likewise passes through 15 without deviation.

Ray 119 in Fig. 10 might appear to be reflected at the cemented surface of the small prism 114, but it really is reflected by 20 the adjacent uncemented surface of the large prism 115.

NOTE 1.—Although the two-prism form of reflector in Fig. 8 is my own original invention, such invention was fairly anticipated 25 in a publication of Lummer and Brodhun, *Zeitschrift für Instrumentenkunde*, vol. 9, Berlin 1889, pages 23 to 25; also Figs. 1 and 3 on page 43; and therefore I do not make any claim to the two-prism 30 reflector *per se*.

NOTE 2.—The preferred form of non-radial cam *kk'* is an adjustable form such as shown in Fig. 57^a of my said Case A, but as before noted all claims on the non- 35 radial cam are made in my said Case A.

NOTE 3.—The images seen in Figs. 38 and 42 of my said Case A correspond, in nature and direction, respectively to those shown in compartment No. 1, and compartment No. 4 of the present Fig. 8.

NOTE 4.—The disclosures made herein, in connection with present Fig. 8, as to the nature and direction of focuser images, though consistent, as remarked in Note 3 45 above, with those originally made in Figs. 38 and 42 of my said Case A, are in direct conflict with the disclosures made in Figs. 7 and 8 of U. S. Patent No. 1,166,932, granted December 28, 1915, to Woodbury; 50 but the house seen in the said Woodbury Figs. 7 and 8, if correctly drawn should have been shown upside down instead of erect.

What I claim as my invention and desire 55 to secure by Letters Patent is:

1. The combination with a photographic camera comprising relatively movable parts adapted to be relatively moved to set the

camera in focus on an object point in the camera field, also an optical focuser of the 60 type comprising means for sighting from two laterally separated points on the focuser or camera convergingly on the same said object point to be focused on, said focuser comprising mirrors located at the said sighting points; one of the said mirrors consisting in a total reflection prism, and means for rendering a part of its hypotenuse face 65 transparent.

2. The combination with a photographic 70 camera comprising relatively movable parts adapted to be relatively moved to set the camera in focus on an object point in the camera field, also an optical focuser of the type comprising means for sighting from 75 two laterally separated points on the focuser or camera convergingly on the same said object point to be focused on, said focuser comprising mirrors located at the said sighting points; one of said mirrors consisting 80 in a total reflection prism, and means for rendering a part of its hypotenuse face transparent, said means consisting in a smaller similar total reflection prism cemented with its hypotenuse face in contact 85 with the hypotenuse face of the said larger prism to annul the reflecting power of that part of the hypotenuse face of the larger prism that is covered by the hypotenuse of the said smaller prism.

3. The combination with a photographic camera comprising relatively movable parts adapted to be relatively moved to set the camera in focus on an object point in the camera field, also an optical focuser of the 95 type comprising means for sighting from two laterally separated points on the focuser or camera convergingly on the same said object point to be focused on; said focuser comprising mirrors located at the said sighting points, and both facing the object; of a divergent lens in the path of rays emitted by the object and reflected by the said 100 mirrors, with its principal axis directed substantially through the said two laterally 105 separated sighting points; and a third mirror fixed in the path of the object rays emitted by the said lens, to reflect such object rays into the observer's eye E as coming from two erect images *j*, *j'*; and means 110 for fixing said third mirror at an angle that is variable to secure any preferred inclination of the line of sight *Ejj'*.

In testimony whereof, I have signed my name to this specification.

JOSEPH BECKER.
